In Germany June 16, 1938

7 Claims. (Cl. 176—122)

The object of the present invention is to provide luminous signs for illuminated advertisements or the like, using vapor, or gas-filled tubes, whereby luminous representations of various kinds can be established in a rapid and simple manner by combining, exchanging or interchanging any desired number of tubes without the necessity of using either individual compensating resistances or individual transformers for the connection of the individual tubes with the common source of current or having to employ a series connection of a plurality of tubes. This applies even if the tubes to be used for the formation of the particular representation desired should differ considerably in size. According to the invention the luminous representation is combined by directly connecting in parallel a number of tubes, each forming a part, e. g., a letter of the representation desired and in which by capacitive means electric fields are produced extending substantially transversely to the tube wall.

In these tubes the current is passed transversely through the vapor, or gas-filled space of the tubes, thereby dispensing with the necessity of applying a different voltage for each different length of tube, as for instance in the case of those known luminous tube appliances in which tubes are used, having their electrodes arranged at the ends of the tube so as to create a current passing lengthwise through each tube. Since in the case of the tubes according to the invention, the same voltage can be used for tubes of very different lengths, such tubes can be directly connected in parallel without resulting in undesired differences of the illuminating effect of the individual tubes.

It is already known, to operate a luminous tube by capacitive means, using external electrodes in such a manner that opposite to the contact points of the electrodes with the tube wall a glow discharge corresponding to the shape of these electrodes is produced in the interior of the tube. In this case the whole luminous representation is effected by one single tube, the external electrodes of which may be exchanged, if desired. It is not the object of this known arrangement, to combine a plurality of differently shaped tubes for the formation of one luminous representation and it has not hitherto been known that the use of transverse currents offers a particularly convenient way of connecting in parallel any number of tubes of various lengths. These tubes may even be of an exceptionally small size.

Electrodes are used with each tube which extend lengthwise of the tube and face each other. One or both of these electrodes may be arranged so as to touch the tube wall either on the outside or inside or may be embedded in the material of the tube wall or may be situated outside of the tube at some distance therefrom. In view of the parallel connection of the tubes, as provided by the invention, it is of particular advantage to arrange one or both electrodes outside the tube wall or to have them embedded therein, because then the wall of each tube acts itself in a desirable manner as a kind of a series-resistance.

Several embodiments of the invention are shown in the accompanying drawings, in which:

Figure 1 represents an elevation partly in section of a sign board,

Figure 2 is a transverse section on the line 2—2 of Figure 1,

Figures 3—5 show transverse sections through luminous tubes, each figure representing another arrangement of the electrodes,

Figure 6 is a transverse section through a further modified form of a tube and its electrodes, and

Figure 7 illustrates in a perspective partial view an arrangement in which the principle shown in Figure 6 is used.

According to Figures 1 and 2, a bracket 2 is fixed on a casing 1 which is open in front, the said bracket supporting a frame 3 of U-shaped cross-section. On the frame 3 are fixed two metal rails 4, 5 which are electrically insulated from one another. A second pair of such metal rails 6, 7 is arranged lower down in the casing 1 in a similar manner to the rails 4, 5. The two pairs of rails 4, 5 and 6, 7 are connected up in parallel to one another and may be connected up through a plug and socket connection 8 to a source of high frequency 11. The source of high frequency is not shown in detail, since various constructions of such high frequency generators are known to those skilled in the art, e. g. induction coils or transmitters and any of these known high frequency generators can be employed.

Finally, lower down still in the casing 1 a third pair of conductor rails 12, 13 is fitted which may be constructed and mounted in the same manner as the conductor rails 4, 5 and 6, 7. The rails 12, 13, however, are shown in the form of two comparatively thick wires, in order to illustrate that various structural forms of the pairs of con-

ductors are possible without departing from the invention.

A plurality of illuminating tubes are connected in parallel to each of the three pairs of conductors 4, 5; 6, 7 and 12, 13 respectively as shown. Each of the tubes is suitably shaped to form a part of the desired illuminated display matter, so that all the tubes connected up in parallel to a pair of conductors together produces the desired illuminated representation. In order to enable the tubes to be connected up in parallel without the assistance of special resistances or the like connected up in series with them, the tubes are constructed in a special manner which will be described in detail in connection with the first tube 14 shown in the sign-board or panel illustrated in Figures 1 and 2.

The illuminating tube 14 comprises a tube 15 of glass or some other suitable transparent or translucent material having the shape of the desired part of the representation, having the shape of the letter Y in the example illustrated. The tube 15 is filled with a rarefied rare gas or the like and is provided on the outside of its walls with conducting strips 16 and 17, all the strips 16 and all the strips 17 being connected up to one another. The tubes may be provided with sockets 18, the contacts 19 and 20 of which are connected up with the conducting strips 16 and 17. If a socket 18 is pushed between the limbs of the carrier 3 then contact springs 19' and 20' connected to the contacts 19 and 20 bear against the conductor rails 4 and 5. If the source of high frequency with which the conductor rails 4 and 5 are connected is switched on, then the conductor strips 16 and 17 carried by the tube 14 act as the plates of a condenser and the tube lights up under the action of the condenser field formed transversely to the axis of the tube, a definite color of light being emitted by the tube corresponding to the gas filling. The color and intensity of the emitted light can be influenced by suitable choice of the gas pressure, the nature and the color of the material from which the tube wall is made (e. g. colored or fluorescent glass, certain artificial resins and the like), the wall thickness of the tubes, and by substances enclosed in the tube which promote the light emitted or vary the color of the light.

By applying suitable substances to the inner wall of the tube it is possible to reduce the ignition tension which can be of considerable importance for starting up the illumination.

The conducting strips 16 and 17 which act as condenser electrodes extend substantially over the entire length of the illuminated character or other element, that is to say, in the case of the example described, the letter Y. The most intensive light action occurs on the wall of the tube in the region of the electrodes 16, 17.

The electrodes 16 and 17 may be constructed in various ways, for instance in the form of coatings applied to the tube wall consisting of a conductive material mixed with a binder, for instance varnish. The electrodes may also be formed by spraying metal on the wall of the tube by the Schoop process or by applying tinfoil coatings, thin wires and so on.

In order to obtain any desired inscription, a plurality of tubes are connected up in parallel, as shown in Figure 1, to the same pair of conductors 4, 5; 6, 7 or 12, 13. In the first line, by way of example, four tubes are used and in the second and third lines eight tubes each. The number of the tubes which may be employed is only limited by the length of the conductor rails 1, 2 and con-

versely in some cases any of the lines of the illuminated panel may only comprise a single tube which in turn may be very small. As shown, the word "York" is formed by the tubes in the first line, the said tubes being of different sizes. Owing to the tubes operating with transversely flowing current however the different lengths of the tubes employed together does not have any detrimental influence on their mode of operation. The same holds good in the case of the word "Franklin" provided in the second line of the illuminated panel and comprising tubes the length of which varies in some cases very considerably from one another. If for instance instead of the four letters comprising the word "York" it is desired to use any other word having more or less letters, then the four tubes shown would be removed and substituted by other tubes inserted between the conductors 4, 5.

Instead of tubes, as above described, each being provided with a socket for connecting them up to the source of current, they may be connected up in some other way, for instance by means of terminals, suspension hooks, rings, brackets, plug contact pins or the like fitted on the rear side of the tube. A method of connecting the tubes to a pair of current conductors by means of clips is shown in the lowermost part (third line of the illuminated panel) illustrated in Figures 1 and 2. The clips, one of which is connected with each electrode of the corresponding tube, are marked 21 and 22.

The condenser electrodes 16, 17 need not be arranged outside of the wall of the tube even though, as already mentioned, it is advantageous for them to be so arranged, but they may comprise conducting strips which are located on the inner wall of the tube (Fig. 3) or are embedded in the glass itself (Fig. 4).

Under certain circumstances it may be of advantage to provide the tubes having the form of letters, written characters or the like with a reflecting coating 17' on the rear side in the manner shown in Figure 5, the said coating being capable of acting as one of the condenser coatings. The other condenser coating 16' may for example be formed by a wire.

It is further not always necessary for the two condenser surfaces to be located directly on the wall of the tube but it may be advantageous in some cases to employ tubes as shown in Figures 6 and 7, in which only one of the condenser electrodes 16'' is carried by the tube wall, the second electrode 17'' of all the tubes is common and formed by a plate situated behind the tubes. The plate 17'' is connected up by means of a wire 23 to one pole of the source of high frequency, while the other pole of the source of high frequency is connected up by means of the conductor 24 to a bus-bar 25 to which the sockets 26 of the illuminating tubes are clamped by means of clamping screws 27. The clamping screws are provided with slots 28 so that the tubes can be displaced easily lengthwise of the bar 25 and can also be readily lifted off for the purpose of exchanging them. In some cases also both condenser electrodes may be arranged separately from the tubes, e. g. in the form of two plates located parallel to one another and between which the tubes are located.

Various effects can be obtained by varying the manner in which the condenser electrodes are constructed and arranged. For instance the electrodes may be made narrow and extend exactly in the vertical central plane of the tubes, so that for instance the shape of a sign com-

prising a letter will be illuminated exactly at the contours so that the letter will be particularly distinct to read. By making the metal coatings wider or narrower, the contour may be made to stand out more or less sharply while by interrupting the coatings, individual parts of the tubes may be prevented from lighting up.

With regard to the use of fluorescent glass for the tube wall, as above mentioned, such fluorescent properties may be utilized in a particularly favourable manner if at least one of the condenser electrodes is in immediate contact with the glass wall, since in this case the glass itself is particularly strongly excited, which also holds good for the substances provided in the tube.

It may further be remarked that the tubes A need not comprise cylindrical tubular elements but may be of any desired shape, as for instance the shape of a figure of an animal or the like.

Owing to the fact that each of the individual tubes excited by current flowing transversely through it is connected up in parallel to the current conductors, the tubes which are connected up in parallel for forming an illuminated representation may be illuminated at different successive intervals by a suitable switching mechanism, a single tube or differently combined groups of tubes being capable of being illuminated at will without any special precaution being necessary in order to allow for different lengths of the tubes.

What we claim is:

1. A gas- or vapor filled luminous tube comprising a transparent envelope substantially in the shape of sign characters and two electrodes arranged exteriorly of the tube filling along lines parallel to the contour lines of the sign character, facing each other along substantially the whole length of the tube, said electrodes being the only electrodes of the tube so as to convey all the energy needed for starting and operating the tube when connected with a high frequency current source, each of the two electrodes consisting of at least one metallic conductor, the conductors belonging to one electrode and the conductors belonging to the other electrode respectively being interconnected on the tube itself.

2. Luminous tube according to claim 1, at least one of the electrodes being in the form of a wire.

3. A gas- or vapor filled luminous tube comprising a transparent envelope substantially in the shape of sign characters and two electrodes secured to the material of said envelope along lines parallel to the contour lines of the sign character, facing each other along substantially the whole length of the tube so as to convey all the energy needed for starting and operating the tube when connected with a high frequency current source, each of the two electrodes consisting of at least one metallic conductor, the conductors belonging to one electrode and the conductors belonging to the other electrode respectively being interconnected on the tube itself.

4. A gas- or vapor filled luminous tube comprising a transparent envelope substantially in the shape of sign characters and two electrodes arranged exteriorly of the tube filling along lines parallel to the contour lines of the sign character, facing each other along substantially the whole length of the tube so as to convey all the

energy needed for starting and operating the tube when connected with a high frequency current source, each of the two electrodes consisting of at least one metallic conductor, the conductors belonging to one electrode and the conductors belonging to the other electrode respectively being interconnected on the tube itself, said metallic conductors being constituted by metallic films applied to the outer surface of the envelope and integrated with the material of said envelope.

5. A gas- or vapor filled luminous tube comprising a transparent envelope substantially in the shape of sign characters and two electrodes applied lengthwise to such envelope for establishing between them electric fields extending substantially transversely to the side walls of said envelope when said electrodes are connected with the two poles respectively of a high frequency current source, said electrodes extending parallel to the contour lines of the sign character for substantially the whole length of said contour lines, at least one of the electrodes being separated from the tube filling by at least a part of the thickness of the material of said envelope, said electrodes being the only electrodes of the tube so as to convey all the energy needed for starting and operating the tube when connected with said high frequency current source, each of the two electrodes consisting of at least one metallic conductor, the conductors belonging to one electrode and the conductors belonging to the other electrode respectively being interconnected on the tube itself.

6. In combination a high frequency current source, a plurality of removable and interchangeable gas- or vapor filled luminous tubes in the shape of sign characters each tube having a transparent envelope, two electrodes firmly applied to said envelope along lines parallel to the contour lines of the respective sign character for substantially the whole length of these contour lines, and means for connecting said electrodes of each tube directly with the high frequency current source, said electrodes being the only electrodes of the tubes so as to convey all the energy needed for starting and operating the tubes, each of the two electrodes of each tube consisting of at least one metallic conductor, the conductors belonging to one electrode and the conductors belonging to the other electrode respectively being interconnected on the tube itself.

7. In combination a high frequency current source, a pair of conductor rails electrically connected with said current source, a plurality of removable and interchangeable gas- or vapor filled luminous tubes in the shape of sign characters each tube having a transparent envelope, two electrodes firmly applied to said envelope along lines parallel to the contour lines of the respective sign character for substantially the whole length of these contour lines, said electrodes being the only electrodes of the tubes so as to convey all the energy needed for starting and operating the tubes, and two contact pieces on each tube connected respectively with the electrodes of that tube and arranged at the same end of the tube for a sliding contact with said pair of conductor rails.
